United States Patent

Des. 236,338
Patented Aug. 19, 1975

236,338

SINGLE HANDLE MARINE ENGINE CONTROL HOUSING

Arthur F. Miller, Oshkosh, Wis., assignor to
Brunswick Corporation, Skokie, Ill.

Filed May 1, 1974, Ser. No. 465,909

Term of patent 14 years

Int. Cl. D12—06

U.S. Cl. D12—179

236,338

FIG. 4

FIG. 5

FIG. 1 is a front perspective view of a single handle marine engine control housing showing my new design;

FIG. 2 is an end elevational view thereof;

FIG. 3 is a fragmentary rear elevational view of the handle;

FIG. 4 is a top plan view thereof; and

FIG. 5 is a bottom plan view thereof.

The rear of the control housing is open and unornamented.

I claim:

The ornamental design for a single handle marine engine control housing, substantially as shown and described.
